ANV

UNITED STATES PATENT OFFICE.

GEORGE M. GEALY, OF GROVE CITY, PENNSYLVANIA, ASSIGNOR TO GEALY WRENCH AND MANUFACTURING COMPANY, OF GROVE CITY, PENNSYLVANIA, A CORPORATION OF PENNSYLVANIA.

PIPE-WRENCH.

1,078,426.

Specification of Letters Patent. Patented Nov. 11, 1913.

Application filed September 21, 1912. Serial No. 721,644.

To all whom it may concern:

Be it known that I, GEORGE M. GEALY, a citizen of the United States of America, residing at Grove City, in the county of Mercer and State of Pennsylvania, have invented certain new and useful Improvements in Pipe-Wrenches, of which the following is a specification, reference being had therein to the accompanying drawing.

10 This is an improvement upon the pipe wrench disclosed in my Patent No. 802,187, granted October 17th, 1905, and besides having the same objects in view as disclosed in my prior patent, the present invention aims 15 to provide a more practical wrench from a manufacturing standpoint, the wrench consisting of parts that are easily assembled, inexpensive to manufacture, durable and highly efficient for the purposes for which 20 it is intended.

The invention further aims to provide a chain wrench that has gripping jaws to which one end of a chain can be easily attached, the opposite end of the chain being 25 connected to a lever supporting the gripping jaws, said lever being arranged in a manner that permits of the jaws being shifted into engagement with a pipe to clamp the chain thereon when leverage is brought to 30 bear upon said lever.

The invention still further aims to accomplish the above results by a mechanical construction that will be hereinafter specifically described and then claimed, and 35 reference will now be had to the drawing, wherein:

Figure 1 is a plan of the wrench as applied to a piece of pipe, Fig. 2 is an enlarged side elevation of the same with the 40 handle of the wrench partly broken away, showing the wrench clamped upon a pipe, Fig. 3 is a similar view showing the wrench upon the pipe but in an unclamped position, Fig. 4 is a perspective view of one of 45 the jaws of the wrench, Fig. 5 is a cross sectional view of the wrench taken on the line V—V of Fig. 2, Fig. 6 is an enlarged plan of a portion of the wrench illustrating a slight modification of the invention, Fig. 50 7 is a side elevation of a portion of a lever used in connection with the wrench shown in Fig. 6, Fig. 8 is an enlarged plan of a portion of a wrench illustrating another modification in connection with the lever thereof, Fig. 9 is 55 a side elevation of the lever shown in Fig.

8, Fig. 10 is an enlarged plan of a portion of a wrench illustrating a still further modification in connection with the lever thereof, Fig. 11 is a side elevation of the lever shown in Fig. 10, and Fig. 12 is an enlarged perspective view of a portion of the modified form of lever, somewhat similar to that illustrated in Fig. 11.

A wrench in accordance with this invention comprises two jaws 1 having the inner ends thereof provided with extensions 2 that are longitudinally slotted, as at 3. The outer ends of the jaws 1 are off-set, as at 4 and provided with V-shaped notches 5 with one wall of each notch provided with transverse teeth 6. The walls of the notches 5 are of greater width than the body of the jaw 1 by reason of the outer side of said body, at the notch 5, being reinforced by a rib 7. The inner sides of the jaws 1 are provided with blocks or enlargements 8, said enlargements having transverse alining openings 9 to receive bolts 10 for holding said jaws in parallelism, the heads 11 of said bolts engaging the outer side of one of said jaws and nuts 12 mounted upon said bolts engaging the outer face of the other jaw. The bolts 10 are arranged in parallelism and firmly hold the enlargements 8 of the jaws together.

The inner faces 13 of the enlargements or blocks 8 are concave to present a bearing surface for the cam-shaped end 14 of a lever 15, said lever being pivotally mounted between the slotted extensions 2 of the jaws by a bolt 16 and a nut 17, said bolt being loosely mounted in the slots 3 of the extensions 2. The lever 12, at the cam end thereof, has the side walls cut away, as at 18 to provide an apertured ear 19 and pivotally connected to said ear by a pin 20 is a link of a chain 21. The chain 21 is of the ordinary and well known type and the links forming the greater part of the chain at the outer end thereof, have the pivot pins projecting from the sides of the link, as at 22 for a purpose that will hereinafter appear.

The inner sides of the jaws 1 are provided with hook-shaped supports 23, these supports being formed integral with said jaws and the enlargements, at the off-set portion 4 of said jaws and in proximity to the toothed walls of the notches 5. The supports 23 are adapted to engage the projecting pivot pins of chain links placed between

the jaws and hold the free end of the chain during the operating of the wrench, which is as follows:—The jaws 1 are placed in engagement with a pipe 24 with the lever 15 in a lowered position, as shown in Fig. 3. The free end of the chain is carried under the pipe and up over the pipe 24, the chain being placed in engagement with the supports 23 with the chain as taut as possible upon the pipe. The lever 15 is then elevated and the cam end 14 thereof rides into engagement with the blocks 8. This movement of the lever 15 tightens the chain upon the pipe 24 and the pipe can be easily rotated.

With particular reference to Figs. 2 and 3 of the drawing, it will be observed in Fig. 3, where the chain 21 is loose, that the pin 20 is in closer proximity to the periphery 20 of the pipe 24 than the bolt 16. Now by reference to Fig. 2, it will be observed that the position of the bolt 16 and the pin 20 is the reverse of that in connection with Fig. 3, that is, the bolt 16 is in closer proximity 25 to the pipe 24 than the pin 20. It is this slight movement of the pin 20 relatively to the bolt 16 that tightens the chain 21 upon the pipe 24 and permits of the pipe being rotated by the wrench. As the chain 21 is 30 tightened by lifting the lever 15, this movement of the lever has a tendency to force the teeth 6 of the jaws into engagement with the periphery of the pipe 24, the teeth engaging in the surface of the pipe and preventing the wrench from slipping during 35 its use.

I attach considerable importance to the slots 3 of the jaws, which permits of the bolt 16 shifting relatively to said jaws and 40 in consequence of this construction a greater tightening action is obtained when the lever 15 is shifted to tighten the chain upon the pipe.

In Figs. 6 to 12 inclusive there are illustrated modifications of my invention, particularly in the manner of connecting the lever 15 to the side extensions 2 of the wrench jaws. As shown in Figs. 6 and 7, the extensions 2 have inwardly projecting 45 studs or pins 24 that extend into an angularly disposed slot 25 provided therefor in the lever 15, the angularity of said slot facilitating the use of the wrench and increasing the leverage of the lever 15. In 50 Figs. 8 and 9 the extensions 2 are slotted to

receive pins 26 carried by the sides of the lever 15 and in Figs. 10 and 11 a bolt 27 and a nut 28 connect the lever to the extensions 2, the lever having an angularly disposed slot 29, similar to the lever shown in Fig. 7. 60 In lieu of the single apertured ear 19 the lever 15 can be provided with two ears 30, as shown in Fig. 12 and a single chain link arranged between said ears.

The wrench in its entirety is made of 65 strong and durable metal and while in the drawing there is illustrated a preferred embodiment of the invention, it is to be understood that the structural elements thereof are susceptible to such variations and modifications as fall within the scope of the appended claim.

What I claim is:—

A pipe wrench comprising a pair of jaw plates having the outer portions thereof offset with respect to the inner portions, said offset portions having their outer edge notched to provide a jaw, the offsetting of said plates forming shoulders, an enlargement integral with the inner face of each 80 of said plates and flush with the shoulder of its respective plate, a hook-shaped support integral with the inner face of each of said plates and with one side of said enlargement and each having a portion flush 85 with the shoulder of its respective plate, said supports of less thickness than said enlargements, said enlargements abutting against each other and provided with alining openings and constituting means for 90 spacing said plates, each of said plates at its inner portion formed with a longitudinally extending slot, means extending through said alining openings and stay-bolts for fixedly securing these latter together, a cam 95 lever mounted between the said bolts, means extending through said slots for loosely connecting the levers to the plates, said lever having its cam end provided with an apertured ear, a chain formed of pivoted links 100 and having the link at one end pivotally connected to said ear, and said chain having the pivots at the outer end thereof projecting from the links.

In testimony whereof I affix my signature 105 in the presence of two witnesses.

GEORGE M. GEALY.
